BY James L. Jenkins

ATTORNEY.

UNITED STATES PATENT OFFICE.

THOMAS J. POLLARD, OF CRANSTON, RHODE ISLAND.

DESIGN FOR A COMBINED COIL BRACELET AND TOY WRIST WATCH.

Application filed July 9, 1923. Serial No. 6,731. Term of patent 3½ years.

To all whom it may concern:

Be it known that I, THOMAS J. POLLARD, a citizen of the United States, residing at Cranston, Rhode Island, have invented a new, original, and ornamental Design for Combined Coil Bracelet and Toy Wrist Watch, of which the following is a specification, reference being had to the accompanying drawing, forming part thereof.

The figure is a front view of a combined coil bracelet and toy wrist watch showing my new design.

I claim:

The ornamental design for a combined coil bracelet and toy wrist watch, as shown.

THOMAS J. POLLARD.
